UNITED STATES PATENT OFFICE.

MITCHELL J. SOMERS, OF SPRINGFIELD, OHIO.

APPARATUS FOR UPSETTING SCREEN WIRE.

Application filed December 5, 1925. Serial No. 73,461.

My present invention relates especially to apparatus for upsetting or crimping screen wire, that is, heavy woven wire, such as used in the manufacture of sand riddles for foundry and other similar uses, and my invention has to do more particularly with the upsetting of regularly spaced apart portions of such woven wire and in such manner as to leave flat portions of the screen between the upset portions and to form relatively sharp angles between the flat portions and the upset portions as well as between the several faces of the upset portions themselves.

The apparatus constituting my present invention is moreover for the specific purpose of producing a sand screen material of the nature described and claimed in my application #29,169, which was filed May 9, 1925, and allowed October 13, 1925, having pyramidal upset portions so shaped and so arranged as to increase effectiveness and efficiency in the same screening operation as well as permit of use of the material in a frame as a sand riddle without additional reinforcement.

The screen material with which my invention is intended for use, is formed in the first instance of woven wire, and subsequent to the upsetting operation for which purpose my present invention is proposed, this material is galvanized or otherwise treated for preservative purposes, and to lock or weld the crossing wires against relative displacement.

It becomes obvious from this that in the upsetting operation the wires of the screening material while woven, are not otherwise connected to one another and are therefore free to stretch during the upsetting operation, as well as to displace one from another should the upsetting operation be carried out without any less than the required care. It is for this purpose that my invention proposes an apparatus which will not only accomplish the upsetting operation, but will do so without risk of displacement of the wires laterally with respect to one another, at their overlapping portions, while permitting their longitudinal stretching.

In the accompanying drawing which illustrates my present invention and forms a part of this specification,

Figure 1 is a front elevation of the two pressure rollers which form the upsetting dies,

Figure 2 is an end view thereof,

Figure 3 is an enlarged detail plan view of a portion of the die surface of the male die,

Figure 4 is a plan view of a small section of the screening material subsequent to the upsetting operation, and

Figure 5 is a sectional view taken on line 5-5 of Figure 4.

Referring now to these figures, and particularly to Figures 1 and 2, I have shown a pair of cylindrical dies including a male die 10, and a female die 11, both of which may be mounted upon shafts 12, suitably connected and actuated in unison whereby screen material including crossed parallel wires 13 as seen in Figure 4, may be fed between the die rollers.

In order that the upsetting of the screen wires 13 may be successfully carried out, it is of course obvious that the rollers or rather the die surfaces of the rollers be made to correspond to the width of the woven material fed therebetween, and for this purpose, it is of course obvious that these rollers may be formed either in one piece or of a sectional built up construction as desired, or as the necessities may require.

It is also obvious that for the upsetting of the screen wires 13 so as to form in the screen a plurality of pyramidal upset portions as indicated at 14 in Figure 5, in such manner as to leave approximately flat portions of the screen between the upset portions and to form between the flat portions and the upset portions as well as between the faces of the upset portions, relatively sharp angles, it is necessary that the male die 10 be provided with pyramidal projections 15 in the definite relation shown over its entire surface to coat with similarly shaped recesses 16 in the female die, and from Figure 3 in particular, it will be noted that the crests or apices of the pyramidal projections 15 of the male die 10 have slots 17 which as plainly seen in Fig. 3 may receive the crossing wires 13 of the screen material and are adapted to prevent lateral displacement of these wires during the upsetting operation and at the same time, leave the wires free to stretch in the direction of their length.

By thus providing for the upsetting of the screen wire through the use of cylindrical male and female dies as proposed by my present apparatus, I permit of the accom-

plishment of the desired operation in a continuous manner and in this way for the economical production of the finished material having the advantages set forth in my application above referred to.

I claim:—

1. An apparatus of the character and for the purpose described, comprising cylindrical male and female upsetting dies, the male die having projections upon its surface provided at their crests with means to engage crossed wire strands and to prevent lateral displacement of such strands while at the

same time permitting lengthwise stretching of the strands for the purpose set forth. 15

2. An apparatus of the character and for the purpose described, comprising cylindrical male and female upsetting dies, the male die having projections and the female die having recesses to receive said projections, 20 and the projections of the male die having at their crests slots adapted to receive crossed wire strands and to prevent lateral displacement of such strands during their lengthwise stretching in the upsetting operation.

MITCHELL J. SOMERS.
